UNDERGARMENT

John A. Boysen, Rutherford, N. J., assignor to
Robert Reis & Co., New York, N. Y., a corpora-
tion of New York

Application October 27, 1938, Serial No. 237,177

1 Claim. (Cl. 2—224)

The invention relates to undergarments and particularly to that type of men's undergarment known in the trade as "shorts," although the invention is equally applicable in the fabrication of garments such as drawers, bathing suits, trousers, and the like.

Undergarments of this general type have heretofore been constructed with front and rear sections constituting the body of the garment, with a narrow insert in substantially rectangular form provided in the back of the garment, the narrow insert constituting and being generally known as an inserted seat. This general practice has been followed for the purpose of economizing on the quantity of material or yardage necessarily embodied in the fabrication of the garment.

Garments constructed in accordance with this practice are characterized by the general objection that by necessity, the seams on the narrow insert are so placed that when the wearer of the garment is seated, the seams cause discomfort and annoyance. Furthermore, the provision of a narrow insert in substantially longitudinally disposed oblong form, results in the inserted seat formed thereby to constitute a constricting area in the back of the garment, so that it is impossible for the back of the garment to assume a free and natural position when the wearer is in sitting posture.

In accordance with my invention, I construct an undergarment of this general type with an inserted seat portion narrow at the top and widening out to a substantial extent at the apex of the seat, so that the seams joining the inserted seat to the body of the garment are positioned at distances sufficiently far from the major portion of the inserted seat, in actual contact with the body when in sitting posture, to eliminate any annoyance or discomfort by the pressure of such seams against the body. Furthermore, in the construction of my novel undergarment, I provide a plurality of pleats in the inserted seat, at substantially the apex of the seat, so that the inseam of the garment is permitted, by reason of the presence of such pleats, to hang in a free and natural position, yielding absolute comfort to the wearer in all positions of the body, particularly when the wearer assumes a sitting posture.

The provision of the pleats at the places indicated, and formed in the particular manner hereinafter described, yields an added fullness of the inserted seat capable of accommodating the shape of the body so as to constitute an undergarment characterized by a well tailored appearance as well as providing a degree of com-

fort not heretofore attained by any construction of the prior art.

Thus, a particular object of my invention is the provision of a man's undergarment having an inserted seat narrow at the top and of substantial width at the apex of the seat, the sides of the seat being arcuate with respect to the vertical center line thereof, such inserted seat being provided at substantially the apex thereof with a plurality of pleats to give a fullness thereto, permitting the garment to hang in a free and natural position and thus afford comfort to the wearer.

A particular embodiment of my invention is illustrated in the accompanying drawings, in which Fig. 1 is a rear view of an undergarment (a pair of shorts) constructed in accordance with my invention; Fig. 2 is a front view of the garment; Fig. 3 is a plan view of the various sections, cut from appropriate patterns, before they are assembled to constitute my novel garment; Fig. 4 is a fragmentary plan view of a portion of the strip of material which is to constitute the inserted seat; Fig. 5 is a plan view of such seat insert portion after the formation of the pleats therein; and Fig. 6 is a section on the line 6—6 of Fig. 1.

Referring more particularly to the drawings, in which similar reference characters identify similar parts in the several views, the garment comprises a body portion formed of two sections of material 7 and 8 joined together at the front of the garment in the conventional manner so as to form the fly 9. To the upper peripheral edges of the sections 7 and 8 are joined by stitching 10 the folded-over strips 11 and 12, constituting the waistband of the garment, with the buttonholes 13 and cooperating buttons 14 provided at the ends of the waistband immediately above the fly 9. The waistband may be provided with the expanding and contracting members 15 and 16, conventional with this type of undergarment, and not herein described in detail as it forms no part of my invention. The body sections 7 and 8 form the usual leg openings 17 and 18 in any suitable and conventional manner.

The novel inserted seat provided in accordance with my invention is constituted of a strip of material 19, which is narrow at the top and widens towards the substantially horizontal center line of the insert, or apex of the seat, and then is curved inwardly toward the bottom of the insert, at which point it is cut out in substantially triangular configuration as at 20. The narrow upper

portion of the insert is provided with a slit 21 which may be seamed as at 22.

The strip of material which is to constitute the seat insert, in the fabrication of my novel undergarment, is provided at each side of the insert approximately at the region of the apex of the insert, with a plurality of notches. Of such notches the first, designated in Figs. 3 and 4 as 22, is substantially at the lower extremity of the edge constituting the upper half of the insert. A somewhat longer notch 23, with a more obtuse angle, is formed immediately adjacent the first notch. At the end of the notch 23 there is formed a third notch 24 which is slightly larger than the notch 22. From the lower extremity of the lower leg of this last notch, the edge of the insert again turns inwardly and then outwardly to form the arcuate peripheral edge of the lower half of the insert.

The provision and setting of the notches along the two side edges of the inserted seat is such that in the process of fabrication of the garment two pleats, generally designated as 25 and 26, are formed by folding over the material extending across the seat between the apices of the notches 22 and 23, in the first instance, and the apex of the notch 24 and the lower extremity of the triangular extension below said notch, in the second instance.

The particular configuration and size of the plurality of notches are such as to insure, when the pleats 25 and 26 have been formed, a continuous curved edge for the seat insert, as shown in Fig. 5, at the widest portion of such insert.

The seat insert thus produced is then laid, in the fabrication of the garment, between the body strips 7 and 8 so that the curved sides of the lower half thereof are in contiguous relation with the inner curved edges of the two strips 7 and 8 and the substantially straight edges of the upper half of the seat insert are in contiguous relation with the straight upper portions of the inner edges of said strips. The said insert, with the pleats therein, formed as above described, are then secured to the body strips 7 and 8 by lines of stitching 27, joining the seamed meeting edges of the respective elements. The pleated seat, at its upper edge is joined to the waistband by the stitching 28 (which may be continuous with stitching 11) and to the lower extremities of the strips 7 and 8 by the sides of the cutout 20 which are stitched to the parts 29 and 30 of such body strips.

The particular construction of the crotch portion of the garment illustrated in the drawings, is not described in detail as any other type of crotch construction may be used in conjunction with my novel seat insert.

In the particular garment selected for illustration, the novel seat insert embodying my invention widens from an approximate width of 7 inches at the top edge thereof, secured to the waistband, to approximately 17 inches in width at the apex of the seat, which apex is substantially at the horizontal median line of the strip constituting the insert. The two pleats provided in a garment of this approximate size are of sufficient width to yield approximately two inches in the fullness of the seat portion of the garment, which is an amount sufficient to accommodate the shape of the body and to permit this particular portion of the garment to hang in a free and natural position. The added fullness thus secured is ample to take care of the shape of the body for both comfort and tailoring.

It is to be understood, of course, that the above figures and measurements are given purely by way of illustration and not by way of limitation, and that the degree of widening of the elastic seat portion and the width of the pleats are dependent entirely upon size of the garment and the person whom it is desired to fit. For the same reason, the provision of two pleats as hereinabove described and illustrated in the drawings, is to be regarded as purely illustrative, as only one, or a greater number than two, of such pleats may be utilized in securing the advantages of my novel undergarment.

While, therefore, I have described a particular embodiment of my invention, it is to be understood that various changes therein, particularly in the arrangement, size and configuration of the various parts thereof, may be made without departing from my invention.

I claim:

An undergarment of the type described, comprising assembled body sections and an inserted seat section of the same material, said body sections extending from the front around the sides to the rear of the garment, and said seat section being constituted of a strip of fabric narrow at its upper edge and widening outwardly along sharply inclined upright edges toward the horizontal central portion thereof, and then curving convexly inwardly toward the bottom edge of the strip, said undergarment being provided with a pleat structure including a plurality of folds extending entirely across said strip and confined to approximately the widest portion thereof at the region intended to surround the maximum girth of the wearer, said strip being seamed along its said widening and curved edges respectively to each of said body sections respectively, substantially in the manner and for the purpose set forth.

JOHN A. BOYSEN.
